SIGNORS TO INTERNATIONAL HARVESTER COMPANY, OF CHICAGO, ILLINOIS, A
CORPORATION OF NEW JERSEY.

COMBINED SHOCK-COMPRESSING AND NEEDLE-SHOCK-ABSORBING MEANS FOR GRAIN SHOCKERS.

Application filed August 18, 1924. Serial No. 732,594.

The present invention relates to grain shocking machines, and particularly to the binding mechanism therefor, having improved means associated with the usual needle thereof for uniformly compressing the shock while the same is being bound with twine in the shock forming receptacle, the same means being adapted also to counterbalance the weight of the needle and prevent hammering and vibration thereof after the same has moved to inoperative position, when the shock tying operation has been completed and the shock has been rearwardly dumped on the ground.

An object of the invention is to provide a simple and efficient self acting means co-operating with the needle for compressing the shock during the binding operation, the same means being adapted to perform the dual function of serving as a shock absorbing and counterbalancing means for the needle when it is moved to normal inoperative position.

A further object is to provide a mechanism of the above character which may be utilized on existing standard type grain shockers without the necessity of greatly modifying its construction and at a minimum of cost.

These objects are attained by the improved mechanism of the present invention, the preferred embodiment of which will be hereinafter described and which has been illustrated in the accompanying sheet of drawings wherein:—

Fig. 1 is a rear elevational view of a grain shucker embodying in its construction the improved shock compressing and needle balancing and shock absorbing means; and

Fig. 2 is a side elevational view of a detail showing the needle mounting and its associated mechanism.

The grain shucker shown is of the standard type embodying an upwardly and rearwardly dumping, normally prostrate, shock forming receptacle 10 pivoted at its rear end as at 11 to the transverse supporting frame member 12 carried on the wheeled frame 13. The supporting frame 12 is provided with the upright standards 14 and 15, the standard 14 on the knotter side of the receptacle supporting the conventional slotted knotter breast plate 16 which cooperates

in the usual way with the arcuate binding needle 17 mounted on a rock shaft 18 journaled in suitable bearings on the opposite side of the receptacle on a frame member 18 longitudinally arranged on the standard 15. The laterally extending bracket 19 bolted to the breast plate 16 carries the knotter shaft 20 which operates the usual knotter milled gear wheel 21 operatively connected by means of the drive chain 22 to a suitable source of power 23.

The knotter shaft 20 has keyed thereto at its rear end a laterally extending arm 24 which in its rotation carries the arm with it, and, through the medium of the link 25, rocks rearwardly the crank 26 carrying a roller 27 at its forward end which pushes upwardly on the receptacle 10 to dump the bound shock in the field. Keyed or otherwise fixed to the forward end of the knotter shaft is another laterally extending arm 28 to which is pivotally connected the pitman 29. The other end of the pitman is pivoted to a depending arm formed as an integral part of a quadrantal gear 30 supported for rocking movement on a shaft carried in a bracket 31 mounted on the standard 15. The quadrantal gear meshes with a quadrantal pinion 32 keyed to the needle shaft 18 for operating it and the needle, of course, with it.

The improved mechanism of this invention comprises a resilient and flexible element carried by the needle and the frame of the shucker for uniformly compressing the shock during the tying thereof, the same element serving to absorb vibration and shock of the needle upon its return movement to normal inoperative position. The structure just referred to includes the coil spring 33 pivotally connected at one end to the arcuate needle, substantially midway between its ends, by means of the eye member 34, the other end being hooked into a chain 35 which has its end fastened to the standard 15 by means of a pin 36 positioned some distance below the needle shaft 18.

In the operation of the grain shucker the power source 23 is tripped into operation by the conventional sheaf delivery fork (not shown) after a predetermined number of sheaves has been piled up in the receptacle 10. The knotter shaft 20 is thus ro-

tated and with it the usual knotting mechanism, the needle 17 in the meantime having been rocked into cooperative position with the knotter to tie the bundles in the receptacle into a shock. While the needle is in this tying position the spring 33 exerts a uniform compressing action on the shock, thereby assisting materially in the formation of a stable shock and one which will better stand in the field when dumped. The knotting operation having been completed, the knotter shaft continues to rotate carrying with it the arm 24, and, through the connections 25, 26 and 27, dumps the receptacle rearwardly to discharge the shock. The needle, of course, is thereupon rocked laterally to inoperative position as shown in dotted lines in Fig. 1, the spring 33 acting to counterbalance its weight and prevent hammering and vibration thereof after it has been thrown back. It has been found desirable to bolt a lug bracket 37 to the upright standard 15 to be engaged by the chain 35 to receive the force of the spring 33 when the needle is thrown back.

From the above description it should be clear that this device achieves all of the objects mentioned at the start of this specification, and that the same is of simple construction, yet dependable in action, and is well adapted to meet the exacting conditions of hard practical use.

It is to be understood that various changes in form, construction, and arrangement of parts may be made by those skilled in the art without departing from the spirit of the invention as claimed.

What is claimed is:—

1. In a shocking machine, a frame, a shock forming receptacle thereon, knotter mechanism disposed at one side of the receptacle, a needle operatively connected to the knotter and disposed at the opposite side of the receptacle, and means connected to the needle and to the frame for exerting a constant pressure on the shock when the needle is in operative position.

2. In a shocking machine, a frame, a shock forming receptacle thereon, knotter mechanism disposed at one side of the receptacle, a needle operatively connected to the knotter and disposed at the opposite side of the receptacle, and means comprising a resilient member connected to the needle and to the frame for exerting a constant pressure on the shock when the needle is in operative position.

3. In a shocking machine, a frame, a shock forming receptacle thereon, knotter mechanism disposed at one side of the receptacle, a needle operatively connected to the knotter and disposed at the opposite side of the receptacle, and means comprising a resilient member and a non-resilient member connected to the needle and to the frame for exert-

ing a constant pressure on the shock when the needle is in operative position.

4. In a shocking machine, a frame, a shock forming receptacle thereon, knotter mechanism disposed at one side of the frame, an arcuate binding needle disposed at the opposite side of the frame and operatively connected to the knotter mechanism, and a chord-like flexible connection having one end connected to the needle intermediate its ends and the other end connected to the frame of the shocker.

5. In a shocking machine, a frame, a shock forming receptacle thereon, knotter mechanism disposed at one side of the frame, an arcuate binding needle disposed at the opposite side of the frame and operatively connected to the knotter mechanism, and a chord-like flexible connection comprising resilient and non-resilient elements connected at one end to the needle intermediate its ends and at the other end to the frame of the shocker.

6. In a shocking machine, a frame, a shock forming receptacle thereon, a knotter mechanism disposed at one side of the frame, a binding needle disposed at the opposite side of the frame and operatively connected to the knotter mechanism, and means for preventing vibration of the needle when the same is moved to inoperative position.

7. In a shocking machine, a frame, a shock forming receptacle thereon, a knotter mechanism disposed at one side of the frame, a binding needle disposed at the opposite side of the frame and operatively connected to the knotter mechanism, and means carried by the needle for preventing vibration thereof when the same has been moved to inoperative position.

8. In a shocking machine, a frame, a shock forming receptacle thereon, a knotter mechanism disposed at one side of the frame, a binding needle disposed at the opposite side of the frame and operatively connected to the knotter mechanism, and resilient means connected to the needle and to the frame for counterbalancing the weight of the needle and preventing vibration thereof when the same has been moved to inoperative position.

9. In a shocking machine, a frame, a shock forming receptacle thereon, a knotter mechanism disposed at one side of the frame, a binding needle disposed at the opposite side of the frame and operatively connected to the knotter mechanism, and means for compressing the shock when the needle is in operative position the same means counterbalancing the weight of the needle and preventing vibration thereof when it is in inoperative position.

10. In a shocking machine, a frame, a shock forming receptacle thereon, a knotter mechanism disposed at one side of the frame,

- a binding needle disposed at the opposite side of the frame and operatively connected to the knotter mechanism, and means connected to the needle and to the frame for compressing the shock when the needle is in operative position the same means counterbalancing the weight of the needle and preventing vibration thereof when it is in inoperative position.
- 10 11. In a shocking machine, a frame, a shock forming receptacle thereon, knotter mechanism disposed at one side of the frame, an arcuate binding needle disposed at the opposite side of the frame and operatively connected to the knotter mechanism, and a chord-like resilient connection connected at one end to the needle intermediate its ends and at the other end to the frame of the shocker for compressing the shock when the needle is in operative position and for counterbalancing the weight of the needle and preventing vibration thereof when the same is in inoperative position.
- 15 12. In a shocking machine, a frame, a shock forming receptacle thereon, knotter mechanism disposed at one side of the frame, an arcuate binding needle disposed at the opposite side of the frame and operatively connected to the knotter mechanism, and a flexible chord-like connection comprising resilient and non-resilient elements carried by the needle and the shocker frame for compressing the shock when the needle is in operative position and for counterbalancing the weight of the needle and preventing vibration thereof when the same is in inoperative position.

In testimony whereof we affix our signatures.
